UNITED STATES PATENT OFFICE.

JOSEPH C. HIGGINS, OF NEW BRUNSWICK, NEW JERSEY.

AUTOMATIC WATER-PIPE-FEEDING ATTACHMENT.

SPECIFICATION forming part of Letters Patent No. 340,313, dated April 20, 1886

Application filed August 1, 1885. Serial No. 173,295. (No model.)

To all whom it may concern:

Be it known that I, JOSEPH C. HIGGINS, a citizen of the United States, residing at New Brunswick, in the county of Middlesex and State of New Jersey, have invented certain new and useful Improvements in Automatic Water-Pipe-Feeding Attachments, of which the following is a specification.

My invention relates to the process of purifying water by impregnating it with a coagulating agent; and the object of my invention is to insert the coagulant, in form of a solution, automatically into water-pipes, for the purpose of saving the time and trouble of first drawing the water and afterward inserting the coagulant. I attain these objects by the mechanism illustrated in the accompanying drawings, in which—

Figure 1 is a cross-section of the entire machine; Fig. 2, a longitudinal section; Fig. 3, end and top view of cylinder; Fig. 4, bottom view of cylinder, cam, and cut-off; and Fig. 5, side and top view of cam.

Similar letters refer to similar parts throughout the several views.

Referring to the drawings, K represents the case or outer covering of the machine. The shaft *a* is supported by and rotates in the bearings J J, which are attached to the inner sides 30 of the case K. This shaft *a* carries an ordinary motor-wheel, H, cam D, and a cylinder, A, all of which are fixed rigidly to said shaft.

The cylinder A is mounted within a cylindrical chamber, *j*, of the box B, and in which it revolves. In the outer surface of the cylinder A is one or more pockets or receptacles, *bb*. The circumference of the cylinder A corresponds exactly in size with the periphery of the cylindrical chamber *j* in the box B, so as 40 to form a perfectly tight-fitting joint. In the upper surface of the box B is an aperture to admit of the passage of liquid from the vessel G through the duct F into the pockets *bb*.

To unload the pockets and prevent them 45 from returning filled with the water from below, I use a cut-off arranged in the following manner: *e* is a horizontal arm extending outward from the side of the box B, and starting from a point just above the aperture *g*. Upon 50 the under side of this arm *e* are two lugs, *d d*, projecting downward and having holes there-

in, which support the handle of a cut-off gate, C. The gate C passes through the aperture *g*, with its upper side lying closely to the upper edge of the aperture.

The inner edge of the gate C rests against the cylinder A. Said gate corresponds in width with that of the aperture *g*. A spiral spring, *c*, is interposed between a pin, *i*, which is inserted through the handle of the cut-off gate C, and the outer lug, *d*, to hold the gate tightly to its place against the cylinder A. This also allows of a backward and forward movement of the gate C, which is necessary in its operation of passing in and out of the pockets *bb*.

To prevent any friction from the cut-off gate C, and thereby prevent wear on the surface of the cylinder A between the pockets *bb*, a spur, *f*, is provided, which projects laterally from the cut-off gate C and extends to a cam, D. This cam gives a reciprocal motion to the cut-off, which raises and drops it automatically off and on the surface of the cylinder at certain required points.

To keep a solid bearing, and prevent leakage from wear between the cylinder A and the upper surface of the cylindrical chamber of the box B, a rod, E, extending downward from the bottom of the box B through the bottom of the case K, can be tightened, when necessary, from the outside of the case K by means of the thumb-nut *h*.

L is the inlet water-pipe, and M the outlet. As the water is put in motion while being 85 drawn off, the force thus produced is thrown on the motor-wheel H from the inlet-pipe at L, which rotates the driving-shaft *a*, and this in turn drives the cylinder A, and by these means the pockets *bb* are filled with the coagulating solution from the vessel G, and are carried around to the opening *g* when the contents of the pockets are forced out clean, and they return empty, as before, ready to receive another charge.

Having thus fully described my invention, what I desire to claim and secure by Letters Patent is—

1. In an automatic water-pipe-feeding attachment, the combination, with the external case, K, of the bearings J J and shaft *a*, carrying a motor-wheel, H, the cam D, the cylinder

- A, having one or more pockets, *bb*, in its outer surface, the induction-pipe F, the box B, and arm e, substantially as herein shown and described.
- 5 2. In an automatic water-pipe-feeding attachment, the combination, with the driving-shaft *a*, which rotates in the bearings *JJ*, of the motor-wheel H, the cam D, the cylinder A, the pockets *bb*, the induction-pipe F, the box B, and the arm e, substantially as herein shown and described.
- 10 3. In an automatic water-pipe-feeding attachment, the combination, with the cylinder A, of the pockets *bb*, the box B, having therein a cylindrical chamber, in which the cylinder A revolves, the axle *a*, and a pipe for conducting water on the motor-wheel H, substantially as herein shown and described.
- 15 4. In an automatic water-pipe-feeding at-
- 20 tachment, the combination, with the box B, of the arm e, extending horizontally from the side of said box B, supporting-lugs *d d*, carrying the cut-off gate C, the spring e, the cylinder A, the cam D, and the spur f, substantially as herein shown and described.
- 25 5. In an automatic water-pipe-feeding attachment, the combination, with the box B, of the tightening-rod E, extending downward from the bottom of the box B through the bottom of the case K, and having the thumb-nut *h* 30 at the lower end, the induction-pipe F, the outer casing, K, and the journal-bearings *JJ*, substantially as herein shown and described.

JOSEPH C. HIGGINS.
